SHIRT JACKET

Louis Blumenstock, Brooklyn, N. Y., assignor to
The Spear Box Co., Inc., a corporation of New
York

Application June 11, 1934, Serial No. 730,082
Renewed July 1, 1938

2 Claims. (Cl. 229—87)

My invention relates to improvements in shirt covers or jackets, and more particularly has reference to and is illustrated in the accompanying drawings in its application to a cover or jacket especially adapted for use with laundered shirts, for protecting the same and for displaying the laundered shirt to advantage.

Referring to said drawings, Fig. 1 shows an application of the same in front elevation with the shirt enclosed. Fig. 2 shows the same opened out in plan view. Fig. 3 shows the upper part of a modified form of jacket. Fig. 4 shows a modified form in front elevation. Fig. 5 an end view looking from right to left thereof. Fig. 6 shows another modified form in front elevation, and Fig. 7 a view looking from right to left thereof.

In the form shown in Figs. 1 and 2, an integral card is formed with a back 8, side portions 9, 10, and front marginal side portions 11, 12, a hole 13 being preferably provided through the back for inspection purposes. At the top, a triangular portion projects with score lines 15, 16, 17, and flaps 18, 19, also a collar insert 20, connected to the triangular portion 14 by a narrow strip 21, and from one of the front side portions is extended a strap 22 having an entering tongue 23 to engage the slit 24, and a center button engaging cut away portion 25.

To insert the shirt, the jacket is laid out flat as shown in Fig. 2, the flaps 18, 19 are turned up at right angles, and the top triangular portion 14 is folded forwardly allowing the flaps 18, 19 to pass into the neck of the shirt. The free ends of the collar support 20 are now inserted beneath the collar, the sides 11, 12 turned over the front of the shirt, and the strap 22 laid across the front of the shirt and engaged at 23, 24, the hole 25 being penetrated by the second button of the shirt. The tie band 22 is preferably cut out of the back of the jacket as shown at 26, and is hinged at 27 as shown.

In the modification shown in Fig. 3 only a base portion 28 of the triangular portion 14 is retained, and is intended to pass up beneath the back of the collar of the shirt.

In the modification shown in Figs. 4 and 5, instead of providing a button hole in the front band, a V 29 is formed with lateral slits 30, 31 to clear the button.

In the modifications shown in Figs. 6 and 7, the front band 32 is preferably cut diagonally from the back as shown, and the tops of the front sides are preferably cut away or beveled as indicated at 33, 34.

Of course it will be understood that various other modifications may be made in the construction and arrangement of parts without departing from the spirit of the invention as claimed.

I claim:

1. In a shirt jacket of the class described, a back portion, side portions, and means for securing a shirt therein, and in combination a neck entering portion, and collar reinforcement, said collar reinforcement connected to said neck entering portion and adapted to be inserted within the collar said reinforcement comprising strips extending laterally from one end of said entering portion, the latter being substantially triangular in plan view with collapsible side flaps.

2. A shirt protector having a flat panel for engaging the body of a shirt, a neck engaging portion extending from the upper edge of the panel, a collar reinforcement connected to said neck engaging portion and adapted to be inserted within the folds of the collar of the shirt, said reinforcement comprising strips extending laterally from the outer end of said neck engaging portion, the neck engaging portion having side flaps for engaging the inner side of the shirt collar, said side flaps being of sufficient depth to resist crushing of the collar.

LOUIS BLUMENSTOCK.
